DEVICE FOR REMOVING FROZEN ICE TRAYS

Herbert H. Tyroff, San Antonio, Tex.

Application February 14, 1933, Serial No. 656,767

7 Claims. (Cl. 254—130)

This invention relates to tools or implements for removing frozen ice trays from mechanical refrigerators and has for its object generally to improve and simplify the construction of such implements whereby to reduce the cost of manufacture and increase the efficiency thereof.

A further object of the invention is to provide an implement of the class described including a standard having a series of notches formed on one side thereof which cooperate with an operating lever to form a fulcrum for the latter when removing an ice tray, said lever being adjustable vertically of the standard whereby to adapt the tool for removing trays of different makes and heights.

A further object is to provide means for preventing accidental separation of the coacting units comprising the tool so that they will always be properly assembled for immediate use, and means whereby the tool may be conveniently suspended from the wire shelf of a refrigerator when the tool is not in use.

A further object is to offset the lower end of the standard so that it will assume a position in front of and adjacent the bottom of the tray to be removed and thereby facilitate dislodgment of said tray from deposits of frost or ice when the operating handle is depressed.

In the accompanying drawing forming a part of this specification:

Figure 1 is a side elevation partly in section, of a tray releasing tool constructed in accordance with the present invention, showing the operating lever in position beneath the reinforcing bead of an ice tray.

Figure 2 is a top plan view of the tool or implement detached.

Figure 3 is a front elevation of the standard.

Figure 4 is a transverse sectional view taken on the line 4—4 of Figure 1.

Figure 5 is a transverse sectional view taken on the line 5—5 of Figure 1.

Similar numerals of reference indicate corresponding parts in all the views of the drawing.

The improved tool or implement forming the subject matter of the present invention comprises an operating lever 5 preferably arcuate in cross section and having one end thereof terminating in a handle 6 and its other end provided with a terminal upwardly inclined lip 7 adapted to extend beneath the reinforcing bead 8 of an ice tray indicated at 9. The front portion of the lever 5 is curved upwardly at 10 and provided with a longitudinal slot 11 and connecting the side walls of the lever immedi-

ately beneath the slot 11 is a transverse bearing pin 12. Associated with the lever 5 is a standard 13 preferably formed of sheet metal and U-shaped in cross section, as shown in Figure 4 of the drawing, thereby providing parallel arms 14 having a series of downwardly and inwardly inclined notches 15 formed therein and opening through the outer longitudinal edges of the arms, as shown. These notches 15 preferably extend substantially the entire height of the standard 13 and are adapted to selectively receive the transverse pin 12 of the operating lever whereby to form a fulcrum on which the lever tilts in the act of dislodging a tray. The lower end of the standard 13 is preferably offset laterally at 16 and extended downwardly to form a foot 17 adapted to rest on the ice or frost in front of and adjacent the bottom of the tray 9 whereby to facilitate dislodgment of said tray when depressing the lever. The metal constituting the arms 14 is inclined downwardly in opposite directions, as indicated at 18 and connected by a transverse bar 19 forming a part of the foot. By making the lower end of the standard in this manner a comparatively wide foot will be produced so as to form a firm foundation for the standard and prevent rocking or tilting movement thereof when operating the tool. The offset portion of the standard is provided with a reinforcing rib 20 which gradually merges into the standard at the bend of the U-shaped portion and also into the foot, thereby to reinforce and strengthen the same. In order to prevent slippage of the standard on the frost or ice within the refrigerator, the foot thereof is provided with a pad 21 preferably formed of rubber, one end of the rubber constituting the pad being extended upwardly at the rear of and in contact with the foot 17 and the other end of the rubber being bent inwardly to form a yieldable locking lip 22 which fits within the hollow portion of the foot and bears against the adjacent side walls thereof. In case the pad 21 becomes worn or otherwise damaged from constant use it may be readily removed by deflecting the lip 22 laterally until it clears the foot and a new pad may then be inserted. The metal at the upper ends of the arms 14 is preferably bent laterally to form retaining ears or stops 23 which serve to prevent accidental separation of the two units comprising the tool so that they will always be properly assembled for immediate use. The end of the handle 6 of the operating lever is also preferably provided with a rearwardly extending hook 23' by means of which the tool

may be conveniently suspended from the wire shelf of a refrigerator when the tool is not in use.

The upper tooth 24 formed by the adjacent notch 15 preferably terminates short of the upper end of the standard 13 and the outer edges of the arms 14 are preferably curved laterally at 25 to assist in guiding the lever to its proper position on the standard when assembling the 10 tool, it being of course understood that after the lever is assembled on the standard, the stop ears 22 will be pressed laterally to prevent separation of the units, as previously stated.

When the device is to be used for removing 15 relatively shallow frozen ice trays the standard is positioned in front of the tray with the lip 7 of the operating lever extending beneath the reinforcing bead 8, after which a downward pressure is exerted on the operating handle 20 which elevates the tray and permits its ready dislodgment from the ice or frost should the tray adhere thereto. In order to remove trays of greater height than that shown in Figure 1 of the drawing, the standard is positioned within 25 the refrigerator in the manner previously stated and the operating lever adjusted vertically on the standard until the lip 7 of the operating lever engages beneath the reinforcing bead of the ice tray to be removed and the pin 12 engages the corresponding notch, after which the 30 handle of the operating lever is depressed in the manner previously described.

It will of course be understood that the tools 35 may be made in different sizes and shapes and either cast or stamped from sheet metal without departing from the spirit of the invention.

Having thus described the invention, what I 40 claim is:

1. A device of the class described comprising 45 a standard substantially U-shaped in cross section and provided with a series of vertically disposed notches, an operating lever fulcrumed on the standard and provided with a transverse pin adapted to engage a selected notch in the standard, and stop ears formed on the standard to prevent accidental separation of said standard and lever.

2. A device of the class described comprising 50 a standard substantially U-shaped in cross section to form spaced arms having notches formed therein and opening through the outer edges of the arms, an operating lever having a longitudinal slot formed therein adapted to receive the arms of the standard and provided with a 55 transverse pin located below the slot and adapted to enter a selected notch, and stop ears extending laterally from the upper end of the standard to prevent withdrawal of the lever from the standard.

60 3. A device of the class described comprising a standard substantially U-shaped in cross section to form spaced arms the outer edges of which are formed with notches, the lower ends of the arms being inclined laterally and downwardly 65 to form a hollow foot, a yieldable pad engaging the foot and having a portion thereof extending

within the hollow foot, and an operating lever slidably mounted for vertical movement on the standard and provided with a transverse pin adapted to enter a selected notch in the arms of said standard.

80 4. A device of the class described comprising a standard substantially U-shaped in cross section to form spaced parallel arms having notches formed in the outer edges thereof, the walls of the arms at the lower end of the standard being inclined laterally and downwardly to form a hollow foot, a transverse cross bar connecting the arms at said foot, a pad of yieldable material surrounding the foot and having a resilient lip adapted to extend within the hollow foot at said 90 cross bar, an operating lever slidably mounted on the standard and provided with a transverse pin adapted to engage a selected notch in the arms, and means on the upper end of the standard for preventing accidental separation of the 95 lever and standard.

5. A device of the class described comprising a standard substantially U-shaped in cross section to form spaced parallel arms having a series of vertical notches formed therein, the lower end 100 of the standard being offset laterally and the walls of the arms being inclined outwardly and laterally at said offset portion to form a hollow foot, there being a reinforcing bead connecting the foot and standard at said offset portion, a 105 pad carried by the foot, and an operating lever having a longitudinal slot therein adapted to receive the standard and provided with a transverse pin beneath the slot adapted to enter a selected notch in the arms of the standard.

110 6. A device of the class described comprising a standard substantially U-shaped in cross section to form spaced arms having a vertical series of notches formed therein, the lower end of the standard being offset laterally to provide a hollow foot and the upper end of the standard being cut away to form a reduced portion, a pad carried by the foot, an operating lever having a lip for engagement with an ice tray and provided with a longitudinal slot adapted to 115 receive the standard, a transverse pin carried by the lever and adapted to enter a selected notch in the standard, and lateral stop ears formed on the upper end of the standard at said reduced portion to prevent removal of the operating lever 120 from the standard.

125 7. A device of the class described comprising a standard having its lower end offset and formed with a laterally enlarged foot, one edge of the standard being provided with a series of 130 vertically disposed notches, an operating lever having an intermediate slot for the reception of the standard and having one end thereof provided with a lip for engagement with an ice tray, a transverse pin carried on the lever beneath the slot and adapted to enter a selected notch in the standard, and stops on the upper end of the standard to prevent accidental removal of the lever from the standard.
